UNITED STATES PATENT OFFICE.

LLEWELLYN JONES, OF NEW CASTLE, PENNSYLVANIA, ASSIGNOR TO AMERICAN SHEET & TIN PLATE COMPANY, OF PITTSBURGH, PENNSYLVANIA, A CORPORATION OF NEW JERSEY.

FEED MECHANISM FOR TINNING OR GALVANIZING MACHINES.

1,117,578.

Specification of Letters Patent. Patented Nov. 17, 1914.

Application filed April 1, 1912. Serial No. 887,782.

To all whom it may concern:

Be it known that I, LLEWELLYN JONES, a citizen of the United States, residing at New Castle, in the county of Lawrence and State 5 of Pennsylvania, have invented certain new and useful Feed Mechanism for Tinning or Galvanizing Machines, of which the following is a specification.

My invention relates to the construction 10 of the feed-out mechanism for tinning and galvanizing machines and more particularly relates to the construction of the rolls used in handling the coated sheets or plates in the passage of the sheets or plates out of 15 the tinning or galvanizing pots and in removing surplus coating metal from the plates emerging from the coating metal in the pots.

The size of rolled sheets and plates has 20 been constantly increasing, both in length and width in recent years, and the increased width of the sheets has necessitated an increase in the width of the pots and required a corresponding increase in the length of the 25 feed-out rolls in coating such sheets and plates. In providing the necessary stiffness and strength in the lengthened rolls, the diameter of these rolls has been materially increased and owing to the increase in the 30 diameter of the rolls the length of the pots has also been increased. Such increase in the length of the pots lengthens the distance the sheets must be fed into the pots by hand, between the guides therein, before the front 35 end of the plates are engaged by the feed-out rolls and makes the operation of feeding the plates to the pots much more difficult and arduous.

One object of this invention is to provide 40 rolls for tinning and galvanizing machines having novel means whereby a material increase in the length of the feed-out rolls may be made without correspondingly increasing the roll diameters and the length of the pots 45 and without lessening the strength and stiffness of the rolls.

Referring to the drawing forming part 50 of this specification, Figure 1 shows a sectional side elevation of a tinning or galvanizing pot having feed-out rolls and roll supporting bearings constructed and arranged in accordance with this invention. Fig. 2 is a plan of the apparatus shown in Fig. 1.

In the drawing, 2 designates a galvaniz-

ing or tinning pot in which the tin, spelter 55 or other coating material is maintained in a molten condition. The pot as shown is provided with guides 3, 4 and 5 and guides 6 and 7, 8 and 9 by means of which the forward ends of the sheets or plates being 60 coated are directed into the bite of one or the other of the two sets of feed-out rolls shown. The lower sets of feed-out rolls 10 and 11, 12 and 13 engage with and feed the 65 coated sheets or plates upwardly into the bite of the upper sets of feed-out rolls 14 and 15, or 16 and 17.

The feed-out rolls are rotatably mounted in bearings of the usual construction at each 70 end thereof which are adjustably secured to the sides of the pot 2 and the top sets of 75 feed-out rolls 14 and 15, 16 and 17 may be provided with wipers or brushes 18 which engage with the roll faces and remove any molten coating metal adhering thereto so as 80 to assist in maintaining the rolls in operative condition and prevent damage to the surfaces of the coated materials passed between the feed-out rolls.

Located at an intermediate point in the 85 length of the feed-out rolls 14 and 17 are the shoes 19 and 20 forming intermediate bearings which contact with the surfaces of these rolls to prevent springing thereof. The shoe 19 is pivoted to the lower end of 90 an arm or lever 21 pivoted at an intermediate point in its length to a bracket 22 which is fastened to the tinning pot 2. The upper end of the arm 21 is provided with a screw-threaded bolt 23 by which the arm is 95 fastened to the pot 2 and is adjusted in holding the shoe 19 in engagement with the feed-out roll 14. The shoe 20 for the feed-out roll 17 is pivoted to one end of the bent knee or bell crank lever 24 which is pivoted 100 to the bracket bearing 25 on the cross bar 26 of the pot 2, and the outer end of the arm 24 of the bell crank lever 24 is adjusted and is held in adjusted position by means of the screw-threaded bolt 27.

Between the feed-out rolls 15 and 16 are the sectional shoes 28, 29, 30 and 31 forming the center bearings engaging with the surfaces of the rolls 15 and 16. These movable, sectional shoes have angular wedging 105 faces which engage with the angular wedging faces 32^a, 33^a of the wedge blocks 32 and 33. The wedge blocks have registering open-

ings or holes therein through which the bolt 34 extends and a helical spring 35 is located between the upper face of the wedge block 32 and the spring follower 36 on the bolt 34, the compression on the spring being regulated by means of the nut 37 on the bolt 34.

By means of the helical spring 35 the sectional wedge blocks 32, 33 are yieldingly held in engagement with the faces of the rolls 15 and 16 so as to prevent springing of these rolls which would otherwise occur, on account of the extreme length and relatively small diameter of the rolls.

In the operation of my improved apparatus, the supply of coating material is maintained in the pot 2 in a molten condition as heretofore and the plates and sheets are fed into, through and out of the coating bath of coating material in the usual known manner. Preparatory to starting the apparatus in operation the bearing blocks 19 and 20 are moved into engagement with the faces of the feed-out rolls 14 and 17 and the nut 37 on the bolt 34 is adjusted to compress the spring 35 and force the wedge blocks 32 and 33 into wedging engagement with the sectional blocks 28, 29, 30 and 31, the sectional blocks in turn being forced outwardly into engagement with the surfaces of the rolls 15 and 16 so that the rolls are supported at three points in their length and spring of the rolls is thereby prevented.

The advantages of my invention will be apparent to those skilled in the art. By providing a bearing contacting with at least one point intermediate of the ends of the rolls the roll diameter can be materially decreased and the length thereof largely increased without liability of flexure.

Modifications in the construction and arrangement of the intermediate bearings and the apparatus holding the intermediate bearing in position may be made without departing from my invention. The invention may be applied for use on a machine employing but one set of rolls as well as on the duplex machine shown and other changes may be made within the scope of my invention as defined in the appended claim. 50

I claim:—

Apparatus for coating metal comprising in combination a pot for the coating metal, a plurality of sets of rolls mounted therein to engage the sheets passed through said pot, said rolls being cylindrical in cross section and arranged to contact with the sheets at all points in the width of the sheets, bearings for the ends of the rolls, intermediate bearings engaging with the outside rolls of the sets and supporting said rolls between the ends thereof, arms pivoted on the pot on which said bearings are mounted, means for moving said arms to adjust and hold said bearings in engagement with said rolls, sectional bearings engaging the adjacent rolls of adjoining sets of rolls at an intermediate point in the length of the rolls, and yielding means engaging with the sectional bearings whereby said bearings are moved 65 and held in engagement with the rolls. 70

In testimony whereof, I have hereunto set my hand.

LLEWELLYN JONES.
